US00D692995S

(12) **United States Design Patent**
Cogswell

(10) **Patent No.:** US D692,995 S
(45) **Date of Patent:** ** Nov. 5, 2013

(54) **ODOR ELIMINATING APPARATUS FOR TOILETS AND THE LIKE**

(71) Applicant: **Potty Fresh Pro LLC**, Ft. Lauderdale, FL (US)

(72) Inventor: **David Lee Cogswell**, Ft. Lauderdale, FL (US)

(73) Assignee: **Cogswell Innovation, Inc.**, Fort Lauderdale, FL (US)

(**) Term: **14 Years**

(21) Appl. No.: **29/452,306**

(22) Filed: **Apr. 15, 2013**

(51) **LOC (9) Cl. 28-99**

(52) **U.S. Cl.**

USPC **D23/366**

(58) **Field of Classification Search**

(57) **CLAIM**

The ornamental design for an odor eliminating apparatus for toilets and the like, as shown and described.

DESCRIPTION

FIG. 1 is a perspective view showing my new design;
FIG. 2 is a top plan view thereof;
FIG. 3 is a front elevational view thereof;
FIG. 4 is a right side elevational view thereof;
FIG. 5 is a left side elevational view thereof;
FIG. 6 is a rear elevational view thereof;
FIG. 7 is a bottom plan view thereof; and,
FIG. 8 is a perspective view showing an odor eliminating apparatus positioned on a toilet.
The broken lines in FIG. 8 showing the toilet and in FIG. 6 showing screws are for the purposes of illustrating environment and form no part of the claimed design.

1 Claim, 5 Drawing Sheets
